FOREIGN PATENT DOCUMENTS

WO D083964-001 * 7/2014

Primary Examiner — Brett Miller*Assistant Examiner* — Rani J Abdallah(74) *Attorney, Agent, or Firm* — Bond Schoeneck & King, PLLC; George McGuire(57) **CLAIM**

The ornamental design for a pump spray bottle, as shown and described.

DESCRIPTION

FIG. 1 is a perspective view of a new and ornamental design for a pump spray bottle;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan elevation view thereof; and,

FIG. 7 is a bottom plan elevation view thereof.

The broken lines shown illustrate portions of the pump spray bottle that form no part of the claimed design.

1 Claim, 6 Drawing Sheets(56)
